UNITED STATES PATENT OFFICE.

WILLIAM C. ANDERSON, OF TOLEDO, OHIO, ASSIGNOR TO THE W. L. LIBBEY & SON COMPANY, OF SAME PLACE.

DESIGN FOR THE ORNAMENTATION OF GLASSWARE.

SPECIFICATION forming part of Design No. 19,450, dated December 3, 1889.

Application filed October 3, 1889. Serial No. 325,931. Term of patent 3½ years.

To all whom it may concern:

Be it known that I, WILLIAM C. ANDERSON, a citizen of the United States, and a resident of Toledo, in the county of Lucas and State of Ohio, have invented and produced a new and original Design for the Ornamentation of Glassware; and I do hereby declare that the following is a full, clear, and exact description of the invention, which will enable others skilled in the art to which it appertains to make and use the same, reference being had to the accompanying drawings, and to the letters of reference marked thereon, which form part of this specification.

The class to which this design relates is that of ornamentation of glassware, and the design pertains to the ornamentation of the exterior surface thereof.

The drawings represent, in Figure 1, a bottom plan view of a dish containing the design, and in Fig. 2 a transverse section on line x x , Fig. 1, this view being drawn on a reduced scale to that of Fig. 1.

The design is applicable to any kind of glassware, such as bowls, plates, jugs, and dishes.

The leading features of my design are hexagonal projections formed by intersecting curvilinear lines with intermediate trapeziform prisms, upon which is a checkering to add to the pleasing effect of the same.

The flattened portion of the bottom A is in

the form of a hexagon, with six trapeziform projections B, with a diamond checkering upon the apices.

C designates hexagonal projections arranged circumferentially of the sides of the dish and formed with a prismatic margin D, of less height than a central circular projection E, formed with a rosette F, inscribed by a many-pointed star F'.

G designates a circumferential row of hexagonal projections of like form and in radial alignment with the projection C, forming inverted-V-shaped spaces G', crossed by acute-angled lines H, thereby forming trapeziform projections I, the apices of which are checkered. The trapeziform projection I, being inscribed by the curvilinear lines, forms a hexagonal figure, thereby preserving the leading feature of the design.

The upper edge of the dish is formed with scallops having projecting points, which give to the dish a finished appearance.

What I claim is—

The design for the ornamentation of glassware herein described and shown.

In testimony that I claim the foregoing as my own I hereby affix my signature in presence of two witnesses.

WILLIAM C. ANDERSON.
